UNITED STATES PATENT OFFICE.

ALBERT O. BUCKIUS, JR., OF CHICAGO, ILLINOIS, ASSIGNOR TO THE NATIONAL
MALLEABLE CASTINGS COMPANY, OF CLEVELAND, OHIO, A CORPORATION OF
OHIO.

JOURNAL-BOX.

1,229,220.

Specification of Letters Patent. Patented June 12, 1917.

Application filed August 15, 1916. Serial No. 114,956.

To all whom it may concern:

Be it known that I, ALBERT O. BUCKIUS, Jr., a citizen of the United States, residing at Chicago, Cook county, Illinois, have invented new and useful Improvements in Journal-Boxes, of which the following is a specification, reference being had to the accompanying drawings, in which—

Figure 1 is an elevation, partly in section, 10 of a journal box embodying my invention; Fig. 2 is a plan thereof, partly in section; Fig. 3 shows a detail of the securing means; Fig. 4 is an elevation, partly in section, of a modified form of my invention; Fig. 5 is 15 a plan thereof, partly in section, and Figs. 6, 7 and 8 show details of the securing key and securing means.

My invention relates to journal boxes, and 20 consists in providing a detachable dust-guard housing, so constructed that it may be easily removed and replaced. My invention also consists in the construction and coöperation of the various parts which I shall hereinafter describe and claim.

25 Referring to the drawings, A indicates the journal box and B the dust-guard housing. The rear end of the box terminates in the inner wall 2 of the dust-guard chamber which acts as a retainer for the oil, as 30 well as a confining wall for the dust-guard. The housing B has the usual opening 3 in its wall 4 of considerably greater diameter than the journal, and between the wall 4 of the housing and the wall 2 is the dust-guard 35 5, intended to fit snugly about the journal and being free to slide upon the journal within the housing. The wall 2 of the box and the wall 4 of the housing are spaced apart by the flanges 6 of the housing, which 40 have a tight fit against the end of the journal box. Upon the sides of the journal box and sides of the housing are cast the lugs 7 and 8 respectively, through which are cored the key passages 9, 10 and 10'. The passage 45 10' is slightly curved and the passage 9 has a projection 11 therein, with which the key 12 coöperates to hold the flanges 6 of the housing tightly against the end of the box. The key 12 is preferably made of spring 50 steel. The upper lug 8 is recessed at 13 for the end of the key, so as to prevent its turning after it has been applied.

When the housing, with the dust-guard in position therein, is applied to the journal

box and the apertures in the lugs 7 and 8 55 brought into register, the keys 12 are then inserted in the position shown in Fig. 3. Each key 12 bears at its ends against the walls of the passages 10, 10', and in its middle portion against the projection 11, and 60 this serves to draw the housing tightly against the end of the journal box and hold the parts in such relation. When the wear which normally occurs on the wall 4 of the housing has rendered the housing unfit for 65 further service, the journal box is removed, the keys 12 withdrawn, and the housing can then be replaced.

Normally, a journal box has to be scrapped when the outer wall of the dust-guard chamber becomes worn to the point of unfitness, 70 but by the use of my invention the life of a box in this regard is greatly increased, since the dust-guard housing may be replaced as often as desired, with a minimum 75 of expense.

In Figs. 4, 5, 6, 7 and 8 I have shown a modification of my device, in which I have provided a journal box housing formed with inner and outer walls 14 and 15, and 80 between which the dust-guard may be inserted through a slot in the top of the housing. In this form I have shown the housing equipped with a single lug 16 on each side, which coöperates with complementary lugs 85 17 on the box, to hold the housing in position. The key 18 bears against the outer faces of the apertures in the lugs 17 and against a projection 19 on the opposite face in the aperture in the lug 16. 90

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed. 95

What I claim is:

1. In journal box mechanism, a removable dust-guard housing comprised of a single piece and embracing a dust-guard, said dust-guard housing being secured to the journal box by wedging means. 100
2. In journal box mechanism, a removable dust-guard housing containing a dust-guard, lugs on the journal box and on the

housing having registering openings, and a key for insertion through said openings to hold the parts in operative position.

3. In journal box mechanism, a removable dust-guard housing containing a dust-guard, lugs on the journal box and on the housing having registering openings, and a key cooperating with wedging faces in said openings to wedge the parts in operative position.

4. In journal box mechanism, a journal box, a removable dust-guard housing, the rear end of the journal box comprising the inner end of the dust-guard chamber, and

the dust-guard housing comprising the top, 15 sides and rear of said chamber, and a dust-guard in said chamber insertible in said housing from the forward open side thereof, said housing being attached to the journal box by wedging means.

5. In journal box mechanism, a removable dust-guard housing containing a dust-guard, the journal box and the housing having registering openings, and a spring key having bearings in the opposite sides of 25 such openings to hold the housing tightly against the journal box.

ALBERT O. BUCKIUS, JR.
